CLAIM

The ornamental design for a vest with cooling member attachments, as shown and described herein.

DESCRIPTION

FIG. 1. Is a perspective view of my vest with cooling member attachments showing my new design in the open position;

FIG. 2. Is a front view of my vest with cooling member attachments thereof in the closed position;

FIG. 3. Is a back view of the vest with cooling member attachments shown in FIG. 2;

FIG. 4. Is a right side elevational view of the vest with cooling member attachments shown in FIG. 2;

FIG. 5. Is a left side elevational view of the vest with cooling member attachments shown in FIG. 2;

FIG. 6. Is a top view of the vest with cooling member attachments shown in FIG. 2; and,

FIG. 7. Is a bottom view of the vest with cooling member attachments shown in FIG. 2.
